(57) **CLAIM**

The ornamental design for a faucet as shown and described.

DESCRIPTION

FIG. 1 is a perspective view of a faucet showing our design; FIG. 2 is a front elevational view;

FIG. 3 is a rear elevational view;

FIG. 4 is a side elevational view;

FIG. 5 is a side elevational view;

FIG. 6 is a top plan view; and

FIG. 7 is a bottom plan view; and,

FIG. 8 is an enlarged view of a portion of FIG. 2 to show detail.

The broken-line disclosures in the drawings represent portions of a faucet that form no part of the claimed design.

1 Claim, 8 Drawing Sheets
